UNITED STATES PATENT OFFICE.

WALTER F. KNOX, OF CHICAGO, ILLINOIS.

RADIATOR HANGER.

Application filed April 21, 1923. Serial No. 633,602.

My invention relates to an improved form of radiator hanger for supporting radiators used for heating purposes from the wall of a building.

As is well known in the art, difficulty is frequently experienced in supporting radiators used for heating purposes which are of the wall type on account of the various spacings of the radiator elements and the further fact that there is no relationship whatever between the parts of the wall to which the fastenings must be secured, for example, the ordinary studding in a plastered wall, and the portions of the radiator to which the fastening devices must be applied. Difficulty is also experienced in this connection frequently as a result of the pipe connections, installed in the building at the time of its erection, not being exactly spaced from the walls as a result of which in mounting one radiator it may be necessary to place it a certain distance from the wall and in mounting a second radiator it may be necessary to place it at a different distance from the wall. Difficulty is also experienced in connection with mounting radiators as above described in so accurately locating the mounting devices vertically that the radiator will be at exactly the desired height when placed on the mounting devices.

By my invention I provide a form of radiator mounting mechanism by which the bases of the mounting devices may be secured to the wall in advance of installing the radiators and, if desired, while the building is in construction, the bases being secured to the parts of the wall, for example, the studding, that are best adapted to support the bases and as long as the bases are mounted on the wall within the outer boundaries of the radiators to be supported thereby, the radiators may subsequently be mounted on the bases in desired position, inasmuch as my improved mounting devices provide for vertical adjustment of the radiator supports on the bases, they provide also for adjustment of the radiator supports on the bases towards and away from the surface of the wall, and they further provide adjustable connections extending laterally from the bases for engaging convenient portions of the radiator what-

ever may be the spacing of its vertical elements, to hold the upper portion of the radiator securely in place, the said devices being adjustable relatively to each other, so that in any case the radiator may be mounted in a vertical plane or parallel with the face of the wall. A further advantage secured by my mounting devices is that they are entirely concealed behind the radiator with the exception of the mounting arms extending underneath the bottom thereof, and they are thin enough in their entirety so that the radiator may be mounted as close to the wall as desirable operating conditions of the radiator will permit.

My improved mounting devices are further adapted to support wall radiators of different types, for example cast iron wall radiators of various designs and constructions and also pipe coil radiators.

My invention will best be understood by reference to the accompanying drawings showing preferred embodiments thereof, in which—

Fig. 1 shows a pair of radiator supports in front elevation with a radiator illustrated in light lines supported thereon,

Fig. 2 shows in side elevation the parts illustrated in Fig. 1,

Fig. 3 shows in front elevation to an enlarged scale, the radiator supporting mechanism shown in Fig. 1,

Fig. 4 shows in side elevation the construction of Fig. 3,

Fig. 5 is a sectional view of the parts shown in Fig. 3 taken along the line 5—5,

Fig. 6 is a fragmentary view showing the upper end of the supporting member engaging the bottom of the radiator shown in Figs. 1 and 2,

Fig. 7 is a plan view of a spacing member preferably employed in the base to support the member shown in Fig. 6,

Fig. 8 shows in front elevation to an enlarged scale the fastening devices extending from the base to support the upper portion of the radiator,

Fig. 9 is a sectional view of the parts shown in Fig. 8 taken along the line 9—9,

Fig. 10 shows in side elevation the lower portion of a modified form of arm for sup-

porting the lower portion of a two cell type of radiator from the base of the mounting devices,

Fig. 11 shows in plan view a modified construction of supporting bracket carried by the base for supporting a radiator of the pipe coil type,

Fig. 12 shows in side elevation the construction illustrated in Fig. 11,

Fig. 13 shows in front elevation the lower portion of the base of the mounting device and a modified supporting device for the type of supporting brackets shown in Figs. 11 and 12, and

Fig. 14 is a sectional view of the parts shown in Fig. 13 taken along the line 14—14.

Similar numerals refer to similar parts throughout the several views.

As shown in Figs. 1 and 2, my mounting mechanism consists essentially of a base 15 supporting in its lower end an outwardly projecting bracket 16 extending below the radiator 17 and having at its upper end a retaining device 18 for engaging the radiator and holding the upper portion thereof in vertical position on the bracket 16. Two of these complete mounting mechanisms are preferably used to support each radiator, although a greater number may be employed 30 in any particular case if necessary or desirable.

As shown in Figs. 3-7 inclusive, the base 15 consists of a piece of sheet metal bent into channel conformation and provided with inwardly extending flanges 15^a extending towards each other to form in effect parallel retaining guideways for receiving the supporting bracket and the upper clamping devices. The bracket 16 is of a width so that it will lie between the inner edges of the flanges 15^a and at its upper end as indicated in Fig. 6, it is provided with trunnions 16^a to extend into the guideways in the base. The bracket is provided at its lower end with an arm 16^b projecting outwardly from the plane of the base and having its upper surface conformed as indicated at 16^c to substantially fit the lower edge of the radiator support thereby.

The base 15 has openings 15^b cut therein as indicated in Fig. 4, for receiving nuts 19 engaging screws 20 extending longitudinally in the said guideways, the openings 15^b being so conformed and of such size that with the screws 20 extending through the nuts 19, both the screws and nuts are held in the position indicated in the drawings and the nuts are prevented from turning when the screws are turned to adjust the parts. The screws 20 support on their upper ends a spacing member 21 which, as indicated in Fig. 7, consists of two side members 21^a of substantially square cross section extending from the upper ends of the screws 20 to the trunnions 16^a, the said side members being connected

together so they are properly contained in the guideways in the base, by a cross member 21^b which preferably is only of sufficient thickness to retain the side members in proper position, so that the bracket 16 where it extends from the trunnions 16^a downwardly over the connecting member 12^b may be of sufficient thickness to possess ample strength and rigidity to support the radiator and at the same time permit the outer face 75 of the vertical portion on the bracket 16 to lie substantially in the plane of the outer surface of the base 15.

The parts described are preferably taken of such dimensions that the arm 16^b is somewhat lower than the heads of the screws 20 so that when the radiator is in place on the supporting mechanism, the only part of the supporting mechanism that will be seen from the front of the radiator is the arm 16^b. From the construction described it will appear that by turning the screws 20 the spacing member 21 is raised or lowered in the guideways as desired and therefore the bracket 16 is correspondingly raised or lowered and in this manner any desired vertical adjustment may be imparted to the supported radiator. It will further be observed that for any adjustment of the screws 20, the relation between the heads of the screws and the arm 16^b referred to, is maintained.

As indicated in Fig. 5, the upper end of the base 15 is preferably provided with an offset 15^e projecting into the channel in the base to prevent the spacing member 21 from sliding out of the base and in this manner the screws 20, the nuts 19 and the spacing member 21 are held in assembled condition after the device is made and before it is put in use. The bracket 16 may be readily removed from the base by swinging it outwardly and then twisting it in a direction to clear the trunnions 16^a from the guideways. In some cases if desired, the spacing member 21 may be omitted and the trunnions 16^a may rest directly upon the upper ends of the screws 20. It will of course be understood that the spacing member 21 when used, may have any desired height to meet the requirements of any particular case and that if desired a plurality of these spacing members may be used in the guideways of the base; also that the base is of any convenient length to place the arms 16^b in desired position under the bottom of the radiator and at the same time to extend high enough so that the clamping mechanism 18 carried by the upper end of the base will positively hold the upper part of the radiator in vertical position.

The bases may be provided through their mid portions with an aperture or apertures 15^d through which suitable screws or bolts 22 may pass to secure the bases against a wall 23 as indicated in Figs. 1 and 2. It

is usually immaterial where the apertures 15^a are placed as long as they are in positions not interfering with the bracket 16 and the upper clamping mechanism 18 and for 5 any special case for which the apertures 15^a must be in some particular position they may be readily punched in the sheet metal in the course of the erection of the devices, by means of the punches usually employed as 10 a part of the erection equipment by steam fitters and pipe fitters.

When the bases 15 are secured to a wall as described, it frequently develops that the radiator must be supported somewhat farther 15 from the wall than provided for by the thickness of the base 15 and the thickness of the vertical portion of the bracket 16. To accomplish this the arm 16^b may be moved outwardly from the base 15 and held 20 in said position by an adjusting screw 24 extending through its lower portion and engaging the base 15. The length of the vertical portion of the bracket 16 is preferably so taken that for any adjustment of the arm 25 16^b away from the wall, the supporting surfaces 16^c will still effectively engage the bottom of the radiator to positively retain it against movement towards or away from the wall unless the radiator is raised bodily 30 from the arms 16^b.

Each of the upper clamping mechanisms 18 consists in part of a screw or bolt 25 extending through one of the apertures of the radiator and provided with a washer 26 at 35 its head end and a nut 27 adjacent the rear face of the radiator, the nut and washer serving to positively engage the radiator and secure the bolt 25 thereto. The remaining parts of each clamping mechanism 18 40 are better illustrated in Figs. 8 and 9 and as shown in said figures, said parts comprise a circular disc 18^a of a diameter slightly less than the width between the inner surfaces of the guideways of the base 15, a 45 washer 18^b of a diameter slightly less than the distance between the inner edges of the flanges 15^a of the base 15 and an arm 18^c, said parts being securely held together by a rivet 18^d or equivalent fastening device. 50 The washer 18^b is of substantially the thickness of the metal of the base 15 and the mounting mechanism is thus adapted to be placed upon and retained by the flanges 15^a which prevent displacement of the mounting 55 means 18 towards or away from the wall 23. The construction however provides that the mounting means 18 may be moved vertically on the base 15 and that the arm 18^c may be turned for any position vertically of the 60 mounting means on the base 15, as desired. The outer end of the arm 18^c is provided with a threaded opening receiving the threaded end of a sleeve 18^e which is internally threaded to receive the end of the bolt 65 25, the length of the sleeve 18^e being pref-

erably sufficient to permit a substantial amount of adjustment of the bolt 25 towards or away from the wall 23 in the sleeve. The distance between the threaded bore of the sleeve 18^e and the center of the disc 18^a is 70 preferably at least half of the maximum spacing of the apertures in the radiators that are to be supported by the mounting devices, as a result of which, whatever may be the position of the radiator on the arms 75 16^b, the arms 18^c may be swung about the centers of the discs 18^a to bring the sleeves 18^e into alignment with the centers of the apertures through the radiator through which the bolts 25 extend. In securing the 80 upper portion of the radiator in desired position by means of the mounting means 18, the bolt 25 is turned in the nut 27 until the radiator is in desired vertical position with the end of the bolt resting against the end of the sleeve 18^e but before there is engagement 85 between the threads of the bolt and the threads of the sleeve. The bolt is then turned in the nut 27 and in the threads in the sleeve 18^e until a clamping engagement 90 of the washer 26 and nut 27 is secured with the radiator, for which condition the same spacing will remain between the nut 27 and the end of the sleeve 18^e as that occurring 95 at the beginning of the turning of the bolt in the sleeve 18^e. When this is done all of the parts of the clamping mechanism 18 are positively held against accidental displacement and the upper portion of the radiator is positively supported in desired vertical position. The sleeve 18^e may be conveniently made of a length permitting its reversal in the arm 18^c, the relation of the 100 parts shown in Figs. 8 and 9 of the drawings providing for the closest possible adjustment of the radiator to the wall permitted by the base 15 and a reversed relation of the sleeve 18^e in the arm 18^c providing for a correspondingly increased and 105 maximum spacing of the radiator from the wall. Obviously any desired spacing of the radiator from the wall may be secured by making the bolts 25 and sleeves 18^e of corresponding length and by making the screws 110 24 of corresponding length. 115

From the above it will be observed that my mounting means provides for vertical adjustment of the radiator as may be required for any particular case even though the bases are secured to the wall before the 120 exact vertical position of the radiator is determined; that they also provide for adjustment of the radiator laterally on the mounting means as may be required by the pipe connections and that they further provide 125 for adjustment of the radiator towards or away from the wall and for maintaining the radiator in vertical position in any adjustment relatively to the wall. It will further be observed that the mounting means is rigid 130

and of substantial construction and furthermore that it is of minimum thickness to secure the results indicated, the only requirements being that the metal of the base shall be sufficiently thick, for example one eighth of an inch, to give ample stability and strength to the base and that the guideways need only to be of sufficient depth to insure that the trunnions 16^a and bracket 16 shall have ample stability and strength. In practice the bracket 16 may be either a casting or a forging and I find a desirable construction to be a steel forging on account of this affording a maximum of strength with a minimum thickness of the bracket.

In some cases the radiator to be supported from the wall consists of a plurality of units each of the kind shown diagrammatically in Figs. 1 and 2 and disposed in parallel relation to each other. The supporting mechanism described may readily be adapted to support radiators of this type by providing a modified bracket 16^a as indicated in Fig. 10 having supporting surfaces 16^e for each of the radiator sections 17^a, the mounting means in other respects being the same as above described.

To facilitate mounting pipe coil radiators from a wall the construction shown in Figs. 11-14 may be employed. In this construction the base 15^a is substantially the same as above described and the bracket construction consists of a sliding member 28 bent to substantially the conformation shown in Fig. 11, with its edge portions rolled as indicated at 28^a to make a sliding fit in the guideways in the base 15^a. The outer portion of the bracket 28 is preferably folded on itself and of double thickness as indicated at 28^b and in this double thickness, circular seats 28^c are formed between which upwardly extending hooks 28^d project to retain the pipes of the pipe coil on the seats 28^e. If desired, the same type of adjustable supporting devices described above and consisting of the nuts 19 and bolts 20 may be used to support the brackets 28. If preferred however, a modified form of supporting mechanism may be used, since the sheet metal construction of the bracket readily adapts itself to forming a clearance opening 28^f within the body of the bracket adjacent to the base 15^a. This modified supporting mechanism is shown in Figs. 13 and 14 and consists of a bracket 29 rigidly secured to the mid-portion of the lower end of the base 15^a by any suitable fastening means for example rivets, the outstanding portion of the bracket 29 being threaded vertically to receive the threaded end of the bolt 30 which carries a washer 31 of somewhat larger diameter than the clearance opening 28^f, so that the lower edge of the bracket 28 rests upon the washer 31. The bracket 29 is contained within the clearance opening 28^f and

turning the screw or bolt 30 therefore serves to move the bracket 28 vertically on the base as desired.

In connection with supporting pipe coils, I find it convenient to use brackets of the kind just referred to in connection with the bracket 28, provided with different numbers of seats 28^c. For example while the bracket 28 is shown as having three seats 28^c and is therefore adapted to engage three pipes of the pipe coil, I also show a second similar bracket 28^f having supporting seats for four pipes of a pipe coil. As is well understood the number of pipes in a pipe coil varies widely in different cases; and by providing a standard construction of brackets of the type shown at 28, having three, four and five seats for the pipes of the coil, these brackets may be used in many combinations to provide a proper support for a pipe coil having any number of pipes and where a plurality of these brackets are employed in the same base, it will be understood that each bracket supports the one immediately above it. It will of course be understood that the brackets for supporting the pipe coils may be made with any desired number of supporting seats and any desired spacing between the seats and that the construction affords ready adjustability of the brackets relatively to the base whatever may be the particular construction of bracket.

While I have shown my invention in the particular embodiments above described, it will be understood that I do not limit myself to this exact construction as I may employ equivalents known to the art at the time of the filing of this application without departing from the scope of the appended claims.

What I claim is:

1. In a radiator hanger, the combination of a formed sheet metal base of channel cross section forming substantially parallel guideways, a bracket having a projecting radiator supporting arm mounted for movement in said guideways, devices for supporting said bracket in desired position in said guideways, said bracket comprising a body portion carrying said supporting arm at its lower end and having projecting lugs engaging said guideways, said lugs being at the upper end of said bracket and comprising trunnions about which the bracket may be turned, and a screw extending through said body portion for moving said bracket on said trunnions to move said supporting arm towards or away from said base as desired.

2. In a radiator hanger, the combination of a formed sheet metal base of channel cross section forming substantially parallel guideways, a bracket having a projecting radiator supporting arm mounted for movement in said guideways, and devices for supporting said bracket in desired position in said

guideways, said devices comprising a screw extending longitudinally in each guideway, and a nut carried by the base for each screw and engaging said screw to retain it in its 5 guideway.

3. In a radiator hanger, the combination of a formed sheet metal base of channel cross section forming substantially parallel guideways, a bracket having a projecting radiator 10 supporting arm mounted for movement in said guideways, and devices for supporting said bracket in desired position in said guideways, said devices comprising a screw extending longitudinally in each guideway, 15 and a nut carried by the base for each screw and engaging said screw to retain it in its guideway, said base having openings formed therein loosely containing said nuts and preventing displacement of said nuts and the 20 screws engaged thereby and preventing also turning of said nuts.

4. In a radiator hanger, the combination of a formed sheet metal base of channel cross section forming substantially parallel 25 guideways, a bracket having a projecting radiator supporting arm mounted for movement in said guideways, and devices for supporting said bracket in desired position in said guideways, said devices comprising a 30 screw extending longitudinally in each guideway, and a nut carried by the base for each screw and engaging said screw to retain it in its guideway, and a spacing member between the ends of said screws and the 35 supported portion of said bracket, said spacing member comprising bars in said guideways and a cross member secured to said bars and retaining them in place.

5. In a radiator hanger, the combination 40 of a formed sheet metal base of channel cross section forming substantially parallel guideways, a bracket having a projecting radiator supporting arm mounted for movement in said guideways, and devices for supporting 45 said bracket in desired position in said guideways, said devices comprising a screw extending longitudinally in each guideway, and a nut carried by the base for each screw and engaging said screw to retain it in its 50 guideway, and a spacing member between the ends of said screws and the supported portion of said bracket, said spacing member comprising bars in said guideways and a cross member secured to said bars and retaining them in place, said base having a 55 projection extending into the path of said spacing member to retain it in said guideways.

6. In a radiator hanger, the combination 60 of a formed sheet metal base of channel cross section forming substantially parallel guideways, a bracket having a projecting radiator supporting arm mounted for movement in said guideways, and devices for supporting 65 said bracket in desired position in said

guideways, said bracket comprising a body portion carrying said supporting arm at its lower end and having projecting lugs engaging said guideways, and said devices comprising a screw extending longitudinally in 70 each guideway, and a nut carried by the base for each screw and engaging said screw to retain it in its guideway, and a spacing member between the ends of said screws and the supported portion of said bracket, said spacing member comprising bars in said guideways and a cross member secured to said bars and retaining them in place.

7. In a radiator hanger, the combination of a formed sheet metal base of channel cross section forming substantially parallel guideways, a bracket having a projecting radiator supporting arm mounted for movement in said guideways, devices for supporting said bracket in desired position in said 80 guideways, said bracket comprising a body portion carrying said supporting arm at its lower end and having projecting lugs engaging said guideways, said lugs being at the upper end of said bracket and comprising 85 trunnions about which the bracket may be turned, and a screw extending through said body portion for moving said bracket on said trunnions to move said supporting arm towards or away from said base as desired, 90 said devices comprising a screw extending longitudinally in each guideway, and a nut carried by the base for each screw and engaging said screw to retain it in its guideway, and a spacing member between the 95 ends of said screws and the supported portion of said bracket, said spacing member comprising bars in said guideways and a cross member secured to said bars and retaining them in place.

8. In a radiator hanger, the combination of a formed sheet metal base of channel cross section forming substantially parallel guideways, a bracket having a projecting radiator supporting arm mounted for movement in said guideways, and devices for supporting said bracket in desired position in said guideways, said bracket comprising a body portion carrying said supporting arm at its lower end and having projecting lugs engaging said guideways, and said devices comprising a screw extending longitudinally in each guideway, and a nut carried by the base for each screw and engaging said screw to retain it in its 110 guideway.

9. In a radiator hanger, the combination of a formed sheet metal base of channel cross section forming substantially parallel guideways, a bracket having a projecting radiator supporting arm mounted for movement in said guideways, devices for supporting said bracket in desired position in said guideways, said bracket comprising a body portion carrying said supporting arm at its lower end and having projecting lugs en- 115

gaging said guideways, said lugs being at the upper end of said bracket and comprising trunnions about which the bracket may be turned, and a screw extending through 5 said body portion for moving said bracket on said trunnions to move said supporting arm towards or away from said base as desired, said devices comprising a screw extending longitudinally in each guideway, and a nut 10 carried by the base for each screw and engaging said screw to retain it in its guideway.

10. In a radiator hanger, the combination 15 of a formed sheet metal base of channel cross section forming substantially parallel guideways, a bracket having a projecting radiator supporting arm mounted for movement in said guideways, and devices for supporting said bracket in desired 20 position in said guideways, said bracket comprising a body portion carrying said supporting arm at its lower end and having projecting lugs engaging said 25 guideways, and said devices comprising a screw extending longitudinally in each guideway, and a nut carried by the base for each screw and engaging said screw to retain it in its guideway, said base having 30 openings formed therein loosely containing said nuts and preventing displacement of said nuts and the screws engaged thereby and preventing also turning of said nuts.

11. In a radiator hanger, the combination 35 of a formed sheet metal base of channel cross section forming substantially parallel guideways, a bracket having a projecting radiator supporting arm mounted for movement in said guideways, devices for supporting said bracket in desired 40 position in said guideways, said bracket comprising a body portion carrying said supporting arm at its lower end and having projecting lugs engaging said guideways, said lugs being at the upper end of said 45 bracket and comprising trunnions about which the bracket may be turned, and a screw extending through said body portion for moving said bracket on said trunnions to move said supporting arm towards or 50 away from said base as desired, said devices comprising a screw extending longitudinally in each guideway, and a nut carried by the base for each screw and engaging said screw to retain it in its guideway, and 55 a spacing member between the ends of said screws and the supported portion of said bracket, said spacing member comprising bars in said guideways and a cross member secured to said bars and retaining them in 60 place.

12. In a radiator hanger, the combination 65 of a formed sheet metal base of channel cross section forming substantially parallel guideways, a bracket having a projecting radiator supporting arm mounted for

movement in said guideways, devices for supporting said bracket in desired position in said guideways, and mechanism carried by the upper portion of said guideways and movable longitudinally thereof for retaining the upper portion of a radiator in desired position, said mechanism comprising a rotatable arm retained at one end for rotary movement in a plane substantially parallel to the base, and a screw projecting 75 from its other end to hold the radiator from tipping on said supporting arm.

13. In a radiator hanger, the combination 80 of a formed sheet metal base of channel cross section forming substantially parallel guideways, a bracket having a projecting radiator supporting arm mounted for movement in said guideways, devices for supporting said bracket in desired position in said guideways, and mechanism carried 85 by the upper portion of said base for retaining the upper portion of a radiator in desired position, said mechanism comprising a rotatable arm provided at one end with an annular groove engaging the 90 flanges of the base channel, and carrying at its other end a projecting screw to hold the radiator from tipping on said supporting arm.

14. In a radiator hanger, the combination 95 of a formed sheet metal base of channel cross section forming substantially parallel guideways, a bracket having a projecting radiator supporting arm mounted for movement in said guideways, devices 100 for supporting said bracket in desired position in said guideways, and mechanism carried by the upper portion of said base for retaining the upper portion of a radiator in desired position, said mechanism comprising a rotatable arm provided at one end with an annular groove engaging the 105 flanges of the base channel, a threaded sleeve extending from its other end, a screw engaging the threads of said sleeve, and devices carried by said screw for engaging the 110 upper portion of a radiator.

15. In a radiator hanger, the combination 115 of a formed sheet metal base of channel cross section forming substantially parallel guideways, a bracket having a projecting radiator supporting arm mounted for movement in said guideways, devices for supporting said bracket in desired position in said guideways, and mechanism carried 120 by the upper portion of said base for retaining the upper portion of a radiator in desired position, said mechanism comprising a rotatable arm provided at one end with an annular groove engaging the 125 flanges of the base channel, an internally threaded sleeve having external threads engaging the other end of said rotatable arm to project from either side thereof as desired, a screw engaging the internal threads 130

of said sleeve, and devices carried by said screw for engaging the upper portion of a radiator.

16. In a radiator hanger, the combination of a formed sheet metal base of channel cross section forming substantially parallel guideways, a bracket having a projecting radiator supporting arm mounted for movement in said guideways, devices for supporting said bracket in desired position in said guideways, and mechanism carried by the upper portion of said base for retaining the upper portion of a radiator in desired position, said mechanism comprising a rotatable arm provided at one end with an annular groove engaging the flanges of the base channel, a threaded sleeve extending from its other end, a screw engaging the threads of said sleeve, and a washer and nut carried by said screw for clamping a radiator at different desired distances from said rotatable arm.

17. In a radiator hanger, the combination of a formed sheet metal base of channel cross section forming substantially parallel guideways, a bracket having a projecting radiator supporting arm mounted for movement in said guideways, devices for supporting said bracket in desired position in said guideways, and mechanism carried by the upper portion of said base for retaining the upper portion of a radiator in desired position, said mechanism comprising a rotatable arm provided at one end with an annular groove engaging the flanges of the base channel, an internally threaded sleeve having external threads engaging the other end of said rotatable arm to project from either side thereof as desired, a screw engaging the internal threads of said sleeve, and a washer and nut carried by said screw for clamping a radiator at different desired distances from said rotatable arm.

18. In a radiator hanger, the combination of a formed sheet metal base of channel cross section forming substantially parallel guideways, a bracket having a projecting radiator supporting arm mounted for movement in said guideways, devices for supporting said bracket in desired position in said guideways, said bracket comprising a body portion carrying said supporting arm at its lower end and having projecting lugs engaging said guideways, and mechanism carried by the upper portion of said base for retaining the upper portion of a radiator in desired position, said mechanism comprising a rotatable arm retained at one end for rotary movement in a plane substantially parallel to the base, and a screw projecting from its other end to hold the radiator from tipping on said supporting arm.

19. In a radiator hanger, the combination of a formed sheet metal base of channel cross section forming substantially parallel guideways, a bracket having a projecting radiator

supporting arm mounted for movement in said guideways, devices for supporting said bracket in desired position in said guideways, said bracket comprising a body portion carrying said supporting arm at its lower end and having projecting lugs engaging said guideways, said lugs being at the upper end of said bracket and comprising trunnions about which the bracket may be turned, a screw extending through said body portion for moving said bracket on said trunnions to move said supporting arm towards or away from said base as desired, and mechanism carried by the upper portion of said base for retaining the upper portion of a radiator in desired position, said mechanism comprising a rotatable arm retained at one end for rotary movement in a plane substantially parallel to the base, and a screw projecting from its other end to hold the radiator from tipping on said supporting arm.

20. In a radiator hanger, the combination of a formed sheet metal base of channel cross section forming substantially parallel guideways, a bracket having a projecting radiator supporting arm mounted for movement in said guideways, devices for supporting said bracket in desired position in said guideways, said bracket comprising a body portion carrying said supporting arm at its lower end and having projecting lugs engaging said guideways, said lugs being at the upper end of said bracket and comprising trunnions about which the bracket may be turned, a screw extending through said body portion for moving said bracket on said trunnions to move said supporting arm towards or away from said base as desired, and mechanism carried by the upper portion of said base for retaining the upper portion of a radiator in desired position, said mechanism comprising a rotatable arm provided at one end with an annular groove engaging the flanges of the base channel, a threaded sleeve extending from its other end, a screw engaging the threads of said sleeve, and devices carried by said screw for engaging the upper portion of a radiator.

21. In a radiator hanger, the combination of a formed sheet metal base of channel cross section forming substantially parallel guideways, a bracket having a projecting radiator supporting arm mounted for movement in said guideways, devices for supporting said bracket in desired position in said guideways, said bracket comprising a body portion carrying said supporting arm at its lower end and having projecting lugs engaging said guideways, said lugs being at the upper end of said bracket and comprising trunnions about which the bracket may be turned, a screw extending through said body portion for moving said bracket on said trunnions to move said supporting arm.

arm towards or away from said base as desired, and mechanism carried by the upper portion of said base for retaining the upper portion of a radiator in desired position, 5 said mechanism comprising a rotatable arm provided at one end with an annular groove engaging the flanges of the base channel, an internally threaded sleeve having external threads engaging the other end of said rotatable arm to project from either side thereof as desired, a screw engaging the internal threads of said sleeve, and devices carried by said screw for engaging the upper portion of a radiator.

15 22. In a radiator hanger, the combination of a base constituting a guiding structure extending longitudinally of the base, a radiator support movable on said structure, devices for moving said support on said structure, 20 and means for moving the supporting end of said support towards or away from said base and holding it in desired position relatively to said base.

25 23. In a radiator hanger, the combination of a base constituting a guiding structure extending longitudinally of the base, a radiator support movable on said structure, devices for moving said support on said structure, and retaining devices carried by said 30 structure and movable longitudinally thereof for engaging and retaining in desired position the upper portion of a radiator, said retaining devices being pivotally connected to said base for movement relatively to said base to engage variously spaced apertures in radiators to be supported by said base.

40 24. In a radiator hanger, the combination of a base constituting a guiding structure extending longitudinally of the base, a radiator support movable on said structure, devices for moving said support on said structure, and retaining devices carried by said structure and movable longitudinally thereof for engaging and retaining in desired position the upper portion of a radiator, said retaining devices being movable towards and away from said structure to secure adjustment of said retaining devices in a first direction and also movable towards and away 45 from the plane of the base to secure adjustment of said retaining devices in a second direction.

55 25. In a radiator hanger, the combination of a base constituting a guiding structure extending longitudinally of the base, a radiator support movable on said structure, devices for moving said support on said structure, means for moving the supporting end of said support towards or away from said 60 base and holding it in desired position relatively to said base, and retaining devices carried by the base for engaging and retaining in desired position the upper portion of a radiator.

65 26. In a radiator hanger, the combination

of a base constituting a guiding structure extending longitudinally of the base, a radiator support movable on said structure, devices for moving said support on said structure, means for moving the supporting end of said support towards or away from said base and holding it in desired position relatively to said base, and retaining devices carried by the base for engaging and retaining in desired position the upper portion of a radiator, said retaining devices being movable relatively to said base to engage variously spaced apertures in radiators to be supported by said base.

70 27. In a radiator hanger, the combination of a base constituting a guiding structure extending longitudinally of the base, a radiator support movable on said structure, devices for moving said support on said structure, means for moving the supporting end of said support towards or away from said base and holding it in desired position relatively to said base, and retaining devices carried by the base for engaging and retaining in desired position the upper portion of a radiator, said retaining devices being movable towards and away from said structure to secure adjustment of said retaining devices in a first direction and also movable towards and away from the plane of the base to secure adjustment of said retaining devices in a second direction.

75 28. In a radiator hanger, the combination of a base having a guiding structure extending longitudinally thereof, a threaded nut carried by the base and separate therefrom with the axis of its threaded portion substantially parallel with said structure, a radiator support mounted for movement on said structure, and a screw in said nut and extending substantially parallel with said structure for supporting said radiator support in desired position on said structure, said structure having an opening receiving a part of said nut to support it, and said screw retaining said nut in said opening.

80 29. In a radiator hanger, the combination of a base having a guiding structure extending longitudinally thereof, a threaded nut carried by the base and readily removable therefrom with the axis of its threaded portion substantially parallel with said structure, a radiator support mounted for movement on said structure, a screw in said nut and extending substantially parallel with said structure for supporting said radiator support in desired position on said structure, and means for moving the supporting portion of said radiator support in a direction substantially at right angles to the plane of said base as desired.

85 30. In a radiator hanger, the combination of a base having a guiding structure extending longitudinally thereof, a threaded nut carried by the base and readily removable

therefrom with the axis of its threaded portion substantially parallel with said structure, a radiator support mounted for movement on said structure, a screw in said nut 5 and extending substantially parallel with said structure for supporting said radiator support in desired position on said structure, and means holding said radiator support in different supporting positions relatively to the base to change the spacing between the lower portion of the radiator and said base as desired.

31. In a radiator hanger, the combination of a base of relatively thin sheet metal of 15 channel formation along its opposite vertical edges constituting substantially parallel retaining guideways, a radiator support movable vertically on said guideways, a threaded nut having a thickness axially of 20 its threaded portion substantially greater than the thickness of the material of the base, said nut being separate from said base and having engagement therewith holding it thereon with its axis substantially parallel 25 with said guideways, a radiator support movable vertically on said guideways, and a screw in said nut for supporting said radiator support.

32. In a radiator hanger, the combination 30 of a base of relatively thin sheet metal of channel formation along its opposite vertical edges constituting substantially parallel retaining guideways, a radiator support movable vertically on said guideways, a 35 threaded nut having a thickness axially of its threaded portion substantially greater than the thickness of the material of the base, said nut being separate from said base and having engagement therewith holding it 40 thereon with its axis substantially parallel with said guideways, a radiator support movable vertically on said guideways, a screw in said nut for supporting said radiator support, and a second screw for changing

the spacing as desired between the radiator 45 support and said base.

33. In a radiator hanger, the combination of a base of relatively thin sheet metal of channel formation along its opposite vertical edges constituting substantially parallel 50 retaining guideways, a radiator support movable vertically on said guideways, a threaded nut having a thickness axially of its threaded portion substantially greater than the thickness of the material of the 55 base, said nut being separate from said base and having engagement therewith holding it thereon with its axis substantially parallel with said guideways, a radiator support movable vertically on said guideways, a 60 screw in said nut for supporting said radiator support, and devices carried by said guideways for engaging and retaining the upper portion of a radiator.

34. In a radiator hanger, the combination 65 of a base of relatively thin sheet metal of channel formation along its opposite vertical edges constituting substantially parallel retaining guideways, a radiator support movable vertically on said guideways, a 70 threaded nut having a thickness axially of its threaded portion substantially greater than the thickness of the material of the base, said nut being separate from said base and having engagement therewith holding 75 it thereon with its axis substantially parallel with said guideways, a radiator support movable vertically on said guideways, a screw in said nut for supporting said radiator support, and devices carried by 80 said guideways for engaging and retaining the upper portion of a radiator, said devices being adjustable to change the spacing between the upper portion of the radiator and said base as desired.

In witness whereof, I hereunto subscribe my name this 14th day of April, A. D. 1928.

WALTER F. KNOX.
